CLOSURE

Frank E. Sweeney, Roselle, N. J., assignor to
Sweeney-Block & Co., Inc., New York, N. Y., a
corporation of New York

Application November 10, 1934, Serial No. 752,539

4 Claims. (Cl. 24—205)

This invention relates to closing means in general, and applicable to various commodities, such as luggage, wearing apparel, etc. and particularly to garments especially adapted for children, 5 wherein a slide fastener is used to disengageably secure certain parts together, an object being to provide a construction of this type which will not catch or get out of order.

Another object of the invention is to provide 10 in a slide fastener construction for a commodity, means which coact with the fastener, but which prevent any pinching or interlocking thereof with the fastener slide.

A further object more specifically is to provide 15 a garment or any other commodity with an opening, located at any desired place, with overlaps provided with thickened edges on both sides of the opening, and means for connecting a slide fastener to such commodity immediately adjacent the opening so that the thickened edges of the overlaps will prevent any part of the fastener sliding mechanism becoming interlocked therewith.

In the accompanying drawing—

25 Figure 1 is a front view of a dress, provided with a closure, constructed in accordance with the present invention;

Fig. 2 is a fragmentary sectional view of Fig. 1 on the line 2—2, the same being on an enlarged 30 scale;

Fig. 3 is a front view of a child's suit with an embodiment of the invention applied thereto;

Fig. 4 is a fragmentary perspective view, partly 35 in section, showing a modified arrangement of a fastener overlap with enlarged or thickened edge;

Fig. 5 is a view similar to Fig. 4 but showing a second modified form of the edge.

Referring to the accompanying drawing by numerals, 1 indicate a dress which is provided 40 with a body 2 open down the front at 3 and provided with the desired neck opening 4. The dress is also provided with sleeves 5 and 6 of any desired kind. It will be observed that the front opening 3 extends from the neck opening 4 downwardly a desired distance, as, for instance, to the point 7. A slide fastener structure 8 is connected to the parts of the body 2 so as to disengageably connect the edges of the opening together.

50 In garments of this kind, which are for small children, the goods are made from thin material and if, for the purpose of forming an overlap for the fastener, an ordinary double thickness at the opening 3 were provided the edges of such overlap would sometimes become punctured by the slide member 9 of the fastener structure 8. As shown in Fig. 2, the slide member 9 is necessarily provided with slots 10 and 11 so as to slide over the tapes 12 and 13. In order for the 55 slide member 9 to move freely, there is provided

a slightly greater opening than the thickness of the tape and, consequently, the edges of the overlaps at the opening 3 sometimes become pinched, and if the strap 14 were given a jerk or hard pull the edge would become torn. For this reason heretofore it has been impossible to use a slide fastener on small children's dresses or in connection with other commodities, where the overlapping edges, adapted to cover the fastener, are made of comparatively thin material. In the 10 present invention, however, means have been provided which will overcome this difficulty, namely, the enlarging of the edges 15 and 16.

As shown in Fig. 2, the edges 15 and 16 are enlarged by having the material looped over and 15 around cords 17 and 18, and then suitable lines of stitching 19 and 20 positioned adjacent the cords so as to provide, in a certain sense, beads. This enlarged rounded structure, which is slightly stiffened by reason of the cords, will not enter 20 the openings 10 and 11, even if brought into contact therewith and, consequently, slide 9 may be moved back and forth freely and carelessly, if desired, without any danger of catching in the side edges of the opening 3. As shown in Fig. 2, 25 the body 2 extends over to the edges 15 and 16, around the cords 17 and 18, and then back to the points 21 and 22. The material is bent back again and looped at 23 and 24, with a small return section so that the lines of stitching 26 and 30 27 may hold the edge of the tapes 12 and 13 firmly in place, lines of stitching 28 and 29 being arranged adjacent the edges 21 and 22. In this way the fastener structure 8 is really suspended 35 from seams 28 and 29. When strap 14 and the operating handle of slide 9 are moved along tapes 12 and 13, they temporarily displace or part the reinforced edges 15 and 16 of the normally adjacent overlaps. However, as soon as they pass, 40 the overlaps retract to their intended, fastener-covering position, being moved together by the stiffness of the reinforcement of their edges, as indicated at 30 in Figure 1, so as to completely hide tapes 12 and 13 and present a pleasing appearance of the entire closure. This arrangement 45 permits the child at any time to open or close the dress at the front without danger of any part of the slide fastener pinching or interlocking any part of the dress.

50 Summarizing, the above described closure consists of a series of adjacent, individual folds or flaps, which are free of one another except that they are held together at their outer edges by stitches 28 and 29. There is a pair of uppermost flaps and another pair of lowermost flaps. The 55 uppermost flaps consist of two folded or doubled single layers or plies of the garment material, the doubling extending over the entire width of the uppermost flaps. Their inner edges are reinforced and are adapted to cooperate with one 60

another and to normally abut at their reinforcements. Below the uppermost flaps there is a pair of lowermost flaps. Each of the lowermost flaps consists of a single ply of garment material ex-

5 tending from stitches 28 and 29 inwards, and terminating in a relatively narrow double layer of material, held together by stitches 26 and 21, which stitches also hold in place tapes 12 and 13 of the slide fastener. The double layer portions of the lowermost flaps form the inner edges thereof, which are placed apart from one another, as clearly seen from Figure 2.

Both uppermost and lowermost flaps are formed from a single ply of the garment material folded upon itself as described, and constitute continuations thereof. The inner edges or margins of the flaps are considered those which are nearest to each other while the outer margins of both flaps coincide with one another and are held together by stitches 28 and 29.

In Fig. 3 the same inventive idea is provided in a boy's suit, the same being indicated by the numeral 31. In this form of garment the opening 3' extends preferably past the waist-line, but otherwise the construction is identical to that shown in Fig. 1 and therefore will need no additional description. In this form of the invention, as well as that shown in Fig. 1, very thin material and cords, as shown in Fig. 2, are preferably used although other forms of edge reinforcement may be employed. For instance, the material may be looped as indicated by 32 in Fig. 4 and strips of the same or of other material 33 inserted. It will be evident that the looping could be made around the strips 33 first, and then held fixed by stitching 19'. This will provide a rounded edge which is somewhat enlarged and which will prevent the overlaps becoming caught by slots 10 and 11 of the slide member 9.

40 Also if preferred, instead of using the cord or filling 33, the edges of the overlaps may be turned upon themselves, as indicated at 34 in Fig. 5, and the line of stitching 19" provided for holding the rolled-up parts together. It will 45 therefore be seen that where the material used is relatively thin, any form of means which will thicken the edge of the overlaps and present a smooth structure will function to prevent the slide member 9 from pinching or interlocking 50 therewith.

In forming garments of the character described without this thickened rounded edge, the slide member 9 will sometimes have pinched the edge of the opening, thus making the garments 55 unsaleable. By providing this thickened rounded edge the slide fastener never pinches or becomes unworkable by reason of the engagement with the edge and, consequently, children or anyone else may operate the slide fastener as often as desired.

60 While I have shown and described my closure in connection with children's garments, and while I have disclosed specific forms thereof, be it understood that my closure may be employed in connection with any other commodity where the 65 sc-called "zipper fastener" is used for drawing together two edges, adapted to be united, and which fastener is to be covered by flaps or overlaps so as to conceal the fastener itself, and I therefore reserve for myself the right to thus employ my invention in connection with any desired commodity, and to make changes and improvements therein without departing from the broad

scope of my idea, as set forth in the annexed claims.

I claim:

1. In a closure for disengageably connecting or drawing together two edges of a commodity made of relatively thin material, an edge construction comprising a single ply of material folded upon itself to form several superimposed adjacent upper and lower double layers, of which layers the upper double layer is provided at its free edge 10 with a reinforcement, while the lowermost double layer forms a free edge, adapted to serve as attaching means for a slide fastener and a slide fastener secured to said lowermost double layer.

2. In a closure for disengageably connecting 15 or drawing together the edges of an opening of a commodity made of relatively thin material, an edge construction formed from the material and comprising a single ply of material folded upon itself to form several adjacent, free upper and 20 lower double layers, the upper double layer having a reinforced free edge, the lowermost double layer forming attaching means, a slide fastener secured to the latter so that the edge-reinforced upper double layer normally overlaps said slide 25 fastener and forms a displaceable and retractable cover means for the latter.

3. In an article made of relatively thin, pliable material and having edges adapted to be closed or drawn together, a closure construction formed 30 from the material of the article, and comprising at each edge a single ply of the material folded so as to constitute two adjacent, superposed flaps, each flap consisting of two folded single layers of material and having free edges, the free edge of 35 one flap materially extending over the free edge of the other flap, the edge of the one flap provided with an edge-reinforcement, a slide fastener having attaching tapes each secured by means of its tape to the free edge of the other flap, the first-mentioned flap adapted to normally overlap said slide fastener and further adapted to be displaceable and retractable when the fastener is being actuated.

4. In a garment made of relatively thin, pliable material, having edges adapted to be closed or drawn together, a closure construction for two corresponding edges formed, in combination, from the garment material itself and a slide fastener having a strap-equipped slide member, said construction comprising, at each of the corresponding edges, a single ply of the garment material, folded so as to form two adjacent flaps, free at their inner margins, but secured together to the single ply of the material at their outer margins, 55 each of the flaps comprising a continuation of the single ply garment material, folded upon itself, one of the flaps being relatively wide and forming the outer cover of the closure and provided with a cord reinforcement at its bent-over, inner margin, the other flap being formed beneath and adjacent to the first-mentioned flap with a bent-over, free, inner margin which is relatively narrow, and its entire width being considerably less than that of the cover flap, a slide fastener, having attaching tapes, secured by means of these tapes to the inner margin of the other flap, the reinforced inner margins of the cover flaps of both corresponding edges adapted to normally 65 abut, while permitting their temporary displacement by the moving slide member and its strap.

FRANK E. SWEENEY.
